US00D771102S

(12) **United States Design Patent** (10) **Patent No.:** **US D771,102 S**
Protzman et al. (45) **Date of Patent:** **** Nov. 8, 2016**

(54) **DISPLAY SCREEN OR PORTION THEREOF WITH GRAPHICAL USER INTERFACE**

(71) Applicant: **Lutron Electronics Co., Inc.**,
Coopersburg, PA (US)

(72) Inventors: **Brent Protzman**, Easton, PA (US);
Michelle L. Greene, Bethlehem, PA (US); **Erica L. Clymer**, Northhampton, PA (US); **Jennifer Wong**, Breinigsville, PA (US); **Samuel F. Chambers**, Gwynedd Valley, PA (US); **Laura Marie Friedlander**, Harleysville, PA (US); **Edward J. Blair**, Telford, PA (US); **Stephen Lundy**, Coopersburg, PA (US); **John N. Callen**, Center Valley, PA (US)

(73) Assignee: **Lutron Electronics Co., Inc.**,
Coopersburg, PA (US)

(**) Term: **14 Years**

(21) Appl. No.: **29/525,154**

(22) Filed: **Apr. 27, 2015**

(51) LOC (10) Cl. **14-04**

(52) U.S. Cl.

USPC **D14/486**

(57) **CLAIM**

The ornamental design for a display screen or portion thereof with graphical user interface, as shown and described.

DESCRIPTION

The sole FIGURE is a display screen or portion thereof with graphical user interface showing our new design.

The peripheral dashed broken lines represent a display screen or portion thereof; the peripheral dashed broken lines form no part of the claimed design.

1 Claim, 1 Drawing Sheet
